FABRIC FOR CURTAINS, DRAPERIES, &c.

o. 18,823.

Patented Dec. 18, 1888

UNITED STATES PATENT OFFICE.

CANDACE WHEELER, OF NEW YORK, N. Y.

DESIGN FOR A FABRIC FOR CURTAINS, DRAPERIES, &c.

SPECIFICATION forming part of Design No. 18,823, dated December 18, 1888.

Application filed November 12, 1888. Serial No. 290,619. Term of patent 7 years.

To all whom it may concern:

Be it known that I, CANDACE WHEELER, a citizen of the United States, residing at New York, in the county of New York and State of New York, have invented a certain new and original Design for Fabrics for Curtains, Draperies, &c.; and I do hereby declare the following to be a full, clear, and exact description of the invention, such as will enable others skilled in the art to which it appertains to make and use the same.

My design is for the ornamentation of fabrics intended particularly for use in curtains, draperies, and hangings.

The accompanying photograph represents a portion of a fabric containing my design, which consists of a groundwork of any suitable color, on which appear groups or bunches of the sweet-pea plant and its flowers tied with ribbon.

A represents the background, of some uniform color or shade; B, a bunch or group of sweet-pea plants with leaves and flowers, and C the ribbon tied around each group.

This design is multiplied or continued over the entire surface of the fabric.

I claim—

The design for the ornamentation of fabrics herein shown and described, the same consisting of a groundwork on which is the representation of groups of sweet-pea plants tied with ribbon.

In testimony whereof I have affixed my signature in presence of two witnesses.

CANDACE WHEELER.
